WILLIAM T. R. PRICE, OF NEW YORK, N. Y., ASSIGNOR TO INTERNATIONAL MOTOR COMPANY, OF NEW YORK, N. Y., A CORPORATION OF DELAWARE.

SPRING CLIP.

1,407,479.

Specification of Letters Patent. Patented Feb. 21, 1922.

Application filed August 28, 1920. Serial No. 406,542.

To all whom it may concern:

Be it known that I, WILLIAM T. R. PRICE, a citizen of the United States, residing in the borough of Manhattan of the city of 5 New York, in the State of New York, have invented certain new and useful Improvements in Spring Clips, of which the following is a specification, reference being had to the accompanying drawing, forming a 10 part hereof.

This invention relates to what may be termed a supplemental spring clip designed for association with the ordinary type of saddle clip now used on leaf springs of 15 motor vehicles. Spring clips as now so often constructed include two U-bolts which pass over the opposite ends of a saddle of some length which may rest on the top side of the spring. These U-bolts may pass 20 through or along the sides of the axle and be drawn on the saddle by nuts at their lower ends. It has been found in practice that it is nearly impossible to set up these bolts sufficiently tight to draw the leaves 25 into intimate and permanent surface contact so as to prevent relative movement therebetween and it is also well nigh impossible to clamp the spring as a unit on the axle with such firmness as to prevent 30 the lowermost leaf from sliding relative to the axle. This creates an insecure and dangerous connection, both as between the various spring leaves of the spring and as between the spring and the axle. The present 35 invention has for its object to provide a supplementary clip for the leaves alone by which they can be securely and permanently drawn together and held against relative movement and by which the spring as a unit 40 can be clamped to the axle and held thereon against relative movement. In the present practise the saddle is not drawn down snugly and uniformly upon assembling since either one end or the other depending 45 upon which is set up first compresses the leaves in its line of draw thereby tending to open them at the distant point where the other bolt rests. The improved clip is 50 secured in place about the leaves and inter mediate the usual U-bolts before the latter are set up. The improved clip further constitutes a pad on which the spring rests and preferably has associated therewith lugs which are engaged by the legs of the 55 U-bolts so as positively to interlock the pad

with the bolts and prevent movement of the pad on the axle. Reference is now to be had to the accompanying drawing for an understanding of a suitable embodiment of the invention, in which—

Figure 1 is a view in side elevation of an improved clip, a fragment of a leaf spring being shown in elevation and the axle being shown in transverse section.

Figure 2 is a view in section taken through the parts shown in Figure 1 but in a plane at right angles thereto.

Figure 3 is a detail sectional view taken along the plane indicated by the broken lines 3—3 of Figure 1 and looking in the direction of the arrows.

Figure 4 is a detail view in side elevation of the improved clip.

Figure 5 is a plan view of a fragment of the improved clip.

In automobile practise, the leaf springs, one of which is indicated generally at *a*, are secured in place on the axle, one type of which is illustrated at *b*. The springs in being secured in place on the axle are 80 engaged by some form of clip which not only serves to secure the leaves together but also holds the spring as a unit in place on the axle. One form of clip is illustrated in the drawing as comprising a saddle piece 85 *c* formed adjacent opposite ends with transverse grooves *c'*, *c*², to receive suitable U-bolts *d*, *d'*, the legs of which snugly embrace the spring *a* and pass through the axle *b* and are engaged at the lower ends by 90 suitable nuts *d*², *d*³, respectively. It has been found in practise in applying such types of spring clips that sufficient pressure on the leaves cannot be obtained to draw them snugly and uniformly into surface contact and secure them permanently in such relation and with sufficient friction to hold them against relative movement. Further, the lowermost leaf which rests on the axle cannot be bound to the axle surface 95 with sufficient friction to prevent slippage therebetween. In accordance with the present invention the saddle *c* is formed intermediate the grooves *c'*, *c*² with ears *c*³, *c*⁴ at opposite sides thereof to receive the upwardly extending threaded legs *e*, *e'* of the improved supplementary clip *e*². The flat body of this clip *e*² is adapted to rest under the spring *a* and form a pad therefor interposed between the spring and the axle. 100

110

By means of this clip the leaves are secured permanently together and held against relative movement. The flat portion e^2 is formed at proper points with ears e^3 , e^4 , 5 etc. to receive the legs of the U-bolts d , d' , respectively. In this way the U-bolts are respectively engaged with the improved clip and since the latter supports the spring as a unit it is insured that there can be no 10 relative movement between the axle and the spring.

In the use of the improved supplemental spring clip it is passed under the spring a at the proper point and the spring set on the axle resting on the pad e^2 which constitutes the web portion of the clip. The saddle c is then placed on the top of the spring, the bolts e , e' of the improved clip passing through the opposed ears c^3 , c^4 of the saddle. Nuts f are then applied to the bolts e , e' and the saddle drawn firmly down on to the top of the spring, the leaves being placed under compression. Since the saddle c will be drawn uniformly down against 15 the top leaf of the spring throughout the 20 length of the saddle all portions of the leaf 25

within the zone of the saddle will be uniformly compressed and no counter stresses can be set up. With the leaves under equal compression in the line of the bolts d , d' , 30 these bolts can then be put in place and set up on tightly, the result being uniform compression of the leaves throughout and a firm union of the spring with the axle.

I claim as my invention:

In combination with the saddle of a spring clip, U-bolts passing over the saddle adjacent opposite ends and extending downwardly through the axle to receive retaining nuts, a supplemental clip having a web 40 section adapted to rest under the spring and formed with ears projecting beyond the sides of the spring through which the legs of said U-bolts pass, and upwardly extending legs formed integrally with the web section and lying between said U-bolts and terminating in threaded portions extending through the saddle to receive retaining nuts. 45

This specification signed this 10 day August, A. D. 1920.
